UNITED STATES PATENT OFFICE.

ADOLPH S. KLEIN, OF CLEVELAND, OHIO.

DISPLAY-CASE.

1,109,339.

Specification of Letters Patent.

Patented Sept. 1, 1914.

Application filed December 22, 1913. Serial No. 808,141.

To all whom it may concern:

Be it known that I, ADOLPH S. KLEIN, a citizen of the United States of America, residing at Cleveland, in the county of 5 Cuyahoga and State of Ohio, have invented certain new and useful Improvements in Display-Cases; and I hereby declare the following to be a full, clear, and exact description of the invention, such as will enable 10 others skilled in the art to which it pertains to make and use the same.

This invention relates to improvements in display-cases, and pertains more especially to a display-case designed for use during 15 such time of the year as is known as the "non-fly" season, but which is readily convertible into a case well adapted for use during such time of the year as is known as the "fly" season.

20 The primary object of this invention is to construct a case of the character indicated which is convenient and simple and durable in construction.

With this object in view, and to the end 25 of attaining any other advantage herein-after appearing, this invention consists in certain structural features, and combinations and arrangement of parts, hereinafter described, pointed out in the claims, and 30 illustrated in the accompanying drawings.

In said drawings, Figure 1 is a front view of a display-case embodying my invention. Fig. 2 is a top plan relative to Fig. 1. Fig. 3 is a vertical section on line 3—3, Fig. 1, 35 looking in the direction indicated by the arrow. Fig. 4 is a vertical section on line 4—4, Fig. 3, looking rearwardly. Fig. 5 is a vertical section illustrative of the manner 40 in which the display-case shown in Figs. 1, 2, 3 and 4 as having its interior chamber in communication with the external atmosphere is converted into a display-case in which said chamber is closed at the top. Fig. 6 is an inner side view of one of the 45 side sections of the hood of the display-case illustrated in Figs. 1, 2, 3 and 4. Fig. 7 is a vertical section on either line 7—7, Fig. 3, looking rearwardly. Fig. 8 is a horizontal section on line 8—8, Fig. 7, looking 50 downwardly. Figs. 3, 4, 5 and 6 are drawn on a larger scale than Figs. 1 and 2, and Figs. 7 and 8 are drawn on a larger scale than Figs. 3, 4, 5 and 6.

55 Referring to the drawings, A indicates the body of a display-case, which body (see Figs. 3, 4 and 7) has an interior chamber

10 for receiving merchandise or other articles. The body A comprises a horizontally arranged quadrangular frame *a* which forms the top of said body and has the opening 12 which extends vertically through said frame forming an inlet of the chamber 10. The opening 12 is larger transversely within the upper portion than within the lower portion of said frame, and the upper transversely larger portion of said opening has two parallel laterally facing side walls 13 (see Figs. 2, 4, 5 and 8) and each of said walls is provided (see Fig. 5) with two metal plates *B* which are spaced longitudinally of the respective wall and secured to said wall, preferably removably by screws *b*, as shown in Fig. 8. Each plate *B* is provided centrally with a laterally and inwardly projecting lug 14 (see Figs. 7 and 8). 75

A hood is arranged over the opening 12 and mounted on the frame *a*, and said hood comprises two laterally spaced substantially vertically arranged side sections *C*, a front section *E* and a top section *G*. The side sections *C* are mounted on the frame *a* at opposite sides respectively of the opening 12 and have portions 16 thereof extending into said opening and from end to end of the walls 13, and each side section *C* is secured at its portion 16 to the adjacent plates *B*, preferably removably by suitably applied thumb-screws 17 which have their heads arranged at the inner sides of said side sections and are screwed into the lugs 14 of said plates. Each side section *C* extends from a point forward of the opening 12 to a point rearward of said opening. 85

Each side section *C* (see Figs. 3, 4 and 95 6) has a sloping forward edge 18 extending upwardly and rearwardly from a point forward of the opening 12, and said side section has a substantially horizontal top edge 20 which extends rearwardly from said 100 sloping edge.

The top section *G* of the hood is removably mounted on the top edges 20 of the side sections *C* and hinged at its forward edge, as at 22, to the front section *E* of the hood and arranged to be swung from the side sections *C* upwardly and forwardly and independently of said front section. 105

The front section *E* is hinged at its lower edge, as at 23, to the frame *a* and arranged to be swung forwardly from the side sections *C* of the hood but leans against the 110

sloping front edges 18 of said side sections, and said side sections are recessed, as at 24, at their inner sides and along their edges 18 and 20 (see Figs. 3, 4 and 6) to accommodate the location of inwardly projecting portions 25 of the front and top sections of the hood.

I would here remark that the sections C, E and G of the hood are preferably composed of wood and glass, but the application of glass panels to wooden frames in the construction or formation of walls or sections of display-cases is too well known in the art to require description in detail in this specification.

By the construction hereinbefore described it will be observed that my improved display-case comprises a body which has an interior chamber having an inlet at the top of the body; that a hood is arranged over said inlet; that said hood is mounted on said body and comprises two laterally spaced side sections, a front section and a top section; that the side sections of the hood rest on the aforesaid body at opposite sides respectively of the aforesaid inlet and are removably secured to said body and extend from a point forward of said inlet to a point rearward of said inlet; that upon swinging the top section of the hood upwardly and forwardly over the outer side of the front section of the hood and thereupon swinging said front section and connected top section far enough forwardly, the side sections of the hood, upon removing the screws 17, are free to be removed from the body of the case, and upon removing said side sections the front and top sections of the hood can be swung into the position shown in Fig. 5 to form a cover for the inlet of the chamber 10, and I would here remark that said top and front sections of the hood are not only large enough in dimensions to cover the opening or inlet 12 when said sections are in the position shown in Fig. 5 but have their inwardly projecting portions 25 arranged as required to project into the upper transversely larger portion of said inlet in said position of said sections.

To positively prevent the ingress of flies or other insects into the case from between the adjacent edges of the front and top sections of the hood in the cover-forming position of said sections the triangular space 26 formed between said cover-forming sections may be filled by a correspondingly shaped bar (not shown).

What I claim is:—

1. In a display-case, the combination, with the body of the case, which body has an interior chamber having an inlet at the top of the body, of a hood arranged over said inlet and mounted on said body and comprising two laterally spaced substantially

vertically arranged side sections, a front section, and a top section, the side sections of the hood being mounted on the aforesaid body at opposite sides respectively of the aforesaid inlet and removably secured to said body, each side section extending from a point forward of said inlet to a point rearward of said inlet, the top section of the hood being removably mounted on said side sections and hinged at its forward edge to the front section of the hood and arranged to be swung from said side sections upwardly and forwardly independently of said front section, and said front section being hinged at its lower edge to the aforesaid body and arranged to be swung forwardly from said side sections.

2. In a display-case, a body which has an interior chamber having an inlet at the top of the body, and a hood arranged over said inlet and mounted on said body and comprising two upright side sections, an upwardly and forwardly facing sloping front section, and a substantially horizontally arranged top section, the side sections of the hood being mounted on the aforesaid body at opposite sides respectively of the aforesaid inlet and removably secured to said body, each side section having a sloping forward edge extending upwardly and rearwardly from a point forward of said inlet, and said side section having a substantially horizontal top edge extending rearwardly from said sloping edge, the top section of the hood being removably mounted on said side sections and hinged at its forward edge to the front section of the hood and arranged to be swung from said side sections upwardly and forwardly, and said front section being hinged at its lower edge to the aforesaid body and arranged to be swung forwardly from said side sections but leaning against the aforesaid sloping edge of each side section of the hood.

3. In a display-case, a body which has an interior chamber having an inlet at the top of the body, and a hood arranged over said inlet and mounted on said body and comprising two upright side sections, a front section, and a substantially horizontally arranged top section, the side sections of the hood being mounted on the aforesaid body at opposite sides respectively of the aforesaid inlet and removably secured to said body, each side section having an upwardly and forwardly facing sloping forward edge and a substantially horizontal top edge and being provided at its inner side with a recess extending along said edges, the top section of the hood being removably mounted on said side sections and hinged at its forward edge to the front section of the hood and arranged to be swung from said side sections upwardly and forwardly, said front section being hinged at its lower edge to the

aforesaid body and leaning against the aforesaid sloping edge of each side section of the hood and arranged to be swung forwardly from the side sections of the hood, 5 and both the front and side sections of the hood having portions thereof projecting into the aforesaid recess.

4. In a display-case, the combination, with the body of the case, which body has an interior chamber and comprises a horizontally arranged quadrangular frame forming the top of said body and having its opening forming an inlet of said chamber, of a hood arranged over said inlet and mounted on 10 said frame and comprising two upright side sections, a front section and a top section, the side sections of the hood being mounted on said frame at opposite sides respectively of the aforesaid opening and removably secured to said frame, each side section extending from a point forward of the said opening to a point rearward of said opening, the top section of the hood being removably mounted on said side sections and hinged at its forward edge to the front section of the hood and arranged to be swung from said side sections upwardly and forwardly, and said front section being hinged at its lower edge to the aforesaid frame and 15 20 25

arranged to be swung forwardly from said side sections.

5. In a display-case, a body which has an interior chamber and comprises a horizontally arranged quadrangular frame forming the top of said body and having its opening forming an inlet of said chamber, which opening is larger transversely within the upper section than within the lower portion of said frame, the upper transversely larger portion of said opening having two parallel 40 side walls, a hood arranged over said opening and mounted on said frame and comprising two upright side sections, a front section and a top section, and metal plates secured to the aforesaid walls, the side sections of the hood being mounted on said frame at opposite sides respectively of said opening and having portions which extend into the upper portion of said opening and from end to end of said walls and are removably secured to said plates. 45 50

In testimony whereof, I sign the foregoing specification, in the presence of two witnesses.

ADOLPH S. KLEIN.
